UNITED STATES PATENT OFFICE.

JOHN W. SMITH, OF PHILADELPHIA, PENNSYLVANIA.

COOLING SYSTEM FOR THE VALVES OF INTERNAL-COMBUSTION ENGINES.

Application filed January 13, 1925. Serial No. 2,054.

This invention, in its broader aspects, comprehends a lubricative-cooling cycle for internal combustion engines characterized by the employment of a cooling medium possessing properties that act as a lubricating agency; or, in other words, the combination of a lubricating and a cooling system into a single cycle. Fundamental to this cycle is a means functional to circulate the fluid medium to the parts to be lubricated and cooled, and also included in said cycle is radiating means effective to dissipate the heat picked up by the fluid medium during circulation.

The primary object of the present invention is directed to the cooling of induction and exhaust valves of internal combustion engines, and is herein illustrated by typical examples that serve to clearly set forth the novel features involved.

It is known that the specific heat of lubricating fluids is less than half that of water with a correspondingly inferior conductivity, hence a comparatively rapid movement of the lubricative-fluid medium over the parts to be cooled must be ensured. Accordingly I arrange within the above referred to cycle suitable circulating means effective to bring about the requisite rapid distribution of the fluid medium. Furthermore, within the cycle a rapid movement of the fluid medium is effected by the reciprocatory action of the induction and exhaust valves, as well as the valve actuating mechanism, such mechanism causing a splashing or pumping of the fluid medium over the parts to be cooled and over a radiator functional to dissipate heat.

The lubricative-cooling cycle also includes a suitable radiator for dissipating heat collected by the fluid medium, said radiator in the typified examples being illustrated as forming some part of the engine; but it is to be explicitly understood such heat dissipating means may be located remote from the engine by the employment of a radiator similar to that used in the well known water cooled system.

Subsidiary objects are the attainment of noiseless valve action with correlated reduction in wear of the moving parts; and a higher compression due to better cooled valves and associated parts.

With the foregoing and other objects in view, which will be apparent from the following description, my invention consists of the matters hereinafter fully set forth, typi-

cally illustrated in the accompanying sheets of drawings, and succinctly defined as to subject-matter and scope by reasonable interpretation accorded the subjoined claims. 60

In the drawings:—

Fig. I, is a side elevation of an enclosed-type internal combustion engine embodying the present improvements, with parts broken away and in section to better illustrate certain underlying features. 65

Fig. II, is an end view of the engine, similarly having parts removed and in section, as well as featuring the circulating connections hereafter more fully described. 70

Fig. III, is an enlarged sectional view through one of the engine cylinders, head and associated valve actuating mechanisms. 75

Fig. IV, is a sectional elevation of another type of internal combustion engine having my invention applied thereto.

Fig. V, is a sectional view of a cam-actuated valve embracing another typical form of the invention; and, 80

Fig. VI, is a fragmentary detail view illustrating a modified location of discharge for the cooling medium circulated through the valve typified by the preceding figure.

Referring to the drawings, like characters of reference designate corresponding parts in all the views, and it is to be understood that while the present application mainly relates to improvements involving cooling of the induction and exhaust valves in internal combustion engines, the invention nevertheless embraces phases susceptible of general application. 85

According to the embodiment shown by Figs. I-III, which illustrate the application of my improvements to an internal combustion engine 7, having an enclosed casing 8 through which air is circulated by means of a fan 9 directly driven by the crankshaft 10, it is to be observed that the engine cylinders 11 are surmounted by a head-block or valve-casing 12 of novel formation. This cylinder head-block or valve-casing 12, as best seen from Fig. III, is designed to provide a fuel intake 13 communicating with the induction manifold 14; and an outlet 15, connecting into the exhaust manifold 15'. Fig. II—as well as a dished cam shaft casing 16 constituting a fluid container which is covered in by means of a radiator cap 17 secured thereto with a fluid-tight joint by stud bolts 18. The aforesaid outlet 15 is conveniently shaped to provide a seat 19 for the

exhaust valve 20, while the induction manifold 14 is mounted on the combustion chamber 12 to receive a valve cage 21, for the induction valve 22, said valve cage being removably held in place by means of a lock collar 23 and stud bolts 24.

The exhaust valve 20—best shown in Fig. III—it will be seen is provided with a tubular stem 25 connecting into an enlarged bulbous head 26 integral with said valve; while the stem 25 is reduced in diameter at 27 forming a cavity to collect the leakage of gases from the combustion chamber, and grooves 28 retard the leakage of said gases as well as assist in preventing an over supply of oil. The valve stem 25 is reciprocably supported in the tubular stem 29 of the induction valve 22, the latter in turn being afforded bearing in the valve cage 21. It is to be noted that the tubular stem 29 is much shorter than the above referred to exhaust valve stem 25, and that it is, also, exteriorly grooved at 30.

The induction valve stem 29 is reduced in diameter at 31 intermediate its end and provided with communicating holes 32, for equalizing the gas pressure in the cavity set up by the reduced part 31 and radial holes 32, while it is made a sliding fit in the valve cage 21. This tubular valve stem 29 is grooved adjacent the outer end to receive a split annular collar 33 locking in place the spring washer 34, that is provided with an annular flange 35, seating one end of a compression spring 36, the other end whereof abuts a rigid washer 37 free about the valve cage 21, as clearly illustrated in Fig. III. Thus it will be readily understood that the tubular valve stem 29 is normally under a spring influence tending to retain the induction valve 22 seated.

The exhaust valve stem 25 is provided with radial holes 38 and externally screw-threaded at its outer end to receive a shouldered nut 39, that supports a spring washer 40, having an annular flange 41 accommodating one end of a valve spring 42, the other end whereof is housed within a substantially U-section support 43, which it will be observed is freely accommodated within the tubular portion 44 of the radiator casing 17—closed in at 45. By slidably fitting the exhaust valve stem 25 through the induction valve stem 29 with provision of the cavities 27, 31 and communicating holes 32, I am enabled to effectively lubricate said stems by a novel means in which gas pressure from the combustion chamber, trapped in the annular cavities 27, 31, is utilized to prevent a surplus of the lubricant cooling medium being pumped through the valve stems into the combustion chamber.

The exhaust valve 20, is comparatively smaller in diameter than the induction valve 22; while the valve cage 21, is fitted in the

counter-bore 76, of the cylinder head 12, with the inner end suitably ground at 77 to provide a seat for the induction valve 22. Thus it will be readily apparent that by removing the radiator 17, each coordinated inlet and exhaust valve unit may be bodily withdrawn for repair, renewal, or cleansing, with a minimum expenditure of time and labor.

The radiator casing 17 is ported to provide an inlet 46, communicating into a feed-pipe 47 of slightly less caliber than the bore of the exhaust valve stem 25 so as to afford an annular clearance 48. An outlet 49 and pipe 50 are provided in the radiator casing 17 for conducting the cooling medium back to the chain drive casing where it is thrown off in a spray by the moving chain and sprocket wheels thus bringing the fluid in contact with the engine casing 7 which functions as an additional cooling means, and from whence it returns to the main reservoir 54.

Suitably supported on an appropriate base 53 in the engine crank case 54 is a force-feed circulating pump 55 driven, by suitable gears 56, from the cam shaft 57 through the medium of a coordinating shaft 58. Distributing communication from the circulating pump 55, to the inlet 46, is afforded through suitable passages 59 in the engine body, or suitable fittings therein, and an exposed pipe 60—Fig. II—which is connected in situ by nipples 61, as will be readily understood by those having ordinary knowledge of such matters.

The means effective to operate and control the induction and exhaust valves 22, 20 respectively, comprise opposingly directed roller arms 62, 63, fulcrumed on shafts 64, 65 journaled lengthwise in the cam shaft casting 16. These roller arms 62, 63, it will be seen, are each fitted with a freely rotatable roller 66 for cooperative engagement by the respective induction and exhaust cams 67, 68 to effect oscillation of said arms. In addition, the roller arms 62, 63 are individually fitted with forked fingers 69, 70 supported on studs 71, with capacity for relative disposition by means of adjusting screws 72, as will be clearly understood by an inspection of Fig. III, while the forked ends of said fingers abut the outer end of the extension tube 31 and the inner end of the shouldered nut 39, as clearly shown in the referred to illustration. The cam shaft 57 is coordinated with the crank shaft 10 by any suitable transmission, such as chain and sprocket drives 73, 74, 75—Fig. I.

Referring now to Fig. IV, which illustrates the adaptation of my improvements to another type of internal combustion engine the parts which, in a general sense, are equivalents of those previously described in detail are correspondingly designated, 130

while the showing has reference to the exhaust valve 20 only. It is, however, to be remarked that the injection tube or feed pipe 47 is stationary, while the valve stem 25 is slidably mounted in a tube 77 fitted into the oblique bearing housing 78, said tube having a flange 79 intermediate its ends, between which end and a collar 80—on the outer end of the stem 25—there is interposed a spring 81 under compression. The means effective in this form of my invention to lift the valve 20, comprises a forked arm 82, pivoted at 83, to a bearer 84 capable of vertical adjustment through the medium of a set screw 85 and slot 86, and to be secured at the desired adjustment by a lock-stud 87, as will be readily appreciated by an examination of the drawings. The forked arm 82 is provided with a roller 66 cooperative with a cam 68 as hereinbefore set forth; while the fluid conducting holes are similarly designated 38, whereas the overflow from the cam shaft casing 16 is by way of an aperture 88 so that said overflow returns directly into the main reservoir 54, with incident splashing of the crank 10'.

In some applications of my invention it may be desirable that the injection tube or feed pipe 47 may be made reciprocatory so as to follow the movements of the valve 20. Such an adaptation of this invention is illustrated by Figs. V and VI; and from which, it will be readily seen that the tube or pipe 47' is in continuation of an adjusting stud 89 screw-threaded into a hollow head 90 having ports 91, 92 affording communication between the inlet 96 and said hollow head. The hollow head 90 is vertically reciprocable in an appropriate guide 93, and it is forked at its lower end to accommodate the roller 66 cooperative with the cam 68 on the cam shaft 57. The guide 93 is rigidly secured in an embossment 94 integral with the cylinder wall 11, and it is provided with an aperture 95 registering into the port 92, above referred to, as well as communicating with the fluid inlet 96. Fluid exit in this type of the invention, from the annular clearance 48 intervening the tube or pipe 47' and the valve stem 25, is by way of elongated slots 97, and an outlet orifice 98. A lock nut 99 serves to secure the adjusting stud 89 and hollow head 90 in rigid connection, while it is preferably provided with a polygonal section or head 100, whereby it may be gripped by a suitable tool when effecting adjustments.

In some instances, instead of providing the elongated slots 97 in the valve stem 25, I may make use of exit ports 101 in the adjusting stud 100, at right angles to the flow through said stem 25, as clearly shown by Fig. VI.

From the foregoing it is thought that the operation of my novel lubricative fluid cool-

ing system whereby both the induction and exhaust valves 22, 20—as well as their stems 29, 25—are effectively cooled and lubricated will be self-evident without further explanation; but it is deemed desirable to emphasize the formation of said valve stems hollow to accommodate the feed tubes 47 or 47', said tubes terminating short of the bulbous heads 26 with provision of the annular clearances 48. Also, in operation, it is to be particularly observed that, the lubricative cooling medium—conventionally designated *m* in the several figures—will be circulated by the pump 55 from the crank case 54, through the passages 59 and pipe 60, into the feed pipe 47 or 47', from which it will emit under forced pressure into the bulbous head 26 of the valve 20, as indicated by the arrows in the different views. As a result of the forced feed for the lubricative cooling medium *m* in the manner stated—it will be apparent that the valve heads will be continuously cooled, while said medium—flowing through the annular clearances 48—similarly cools the valve stems 25, 29. Simultaneously some of the lubricative cooling medium *m* will enter the holes 38 and work into the grooves 28, 30 and by capillary attraction effectively lubricate the respective valve stems 25, 29. Obviously discharge of the lubricative cooling medium *m* from the outer ends of the valve stems 25, 29 flows into the cam-shaft casing 16, where it serves to lubricate the valve actuating mechanism, whereas the overflow returns by way of the conduit 50 or outlet 88, to the main reservoir 54, in the manner, and for the purposes, hereinbefore set forth. Incidentally, it is noteworthy that the reservoir 54 also acts as a radiator for dissipating the heat of the cooling fluid *m*. Another important phase of my invention is the use of a lubricative cooling medium, and in this connection, such medium is to be considered as including all fluent matter possessing the dual properties of lubricating and cooling when circulated in the manner hereinbefore set forth.

Attention is likewise directed to the adequate cooling surface afforded the cam-shaft casing radiator 17—against which the fluid is splashed—by providing the upper part 17' thereof with cooling fins "f" about which air is circulated by the fan 9. However, valves cooled by the lubricative-fluid medium, in the manner set forth hereinbefore, may not require such additional radiating means when used in connection with the well known water-cooling systems, since the excess heat of the fluid medium would be dissipated through contact with the water cooled zone.

In conclusion, it will be obvious that I have devised a novel and useful lubricating-fluid cooling system which constitutes a cooling

and lubricating cycle, and that it also embodies all the features and advantages enumerated as desirable in the statement of invention. Again the foregoing disclosure, exemplifies the gist of this invention in a manner whereby others—by applying current knowledge—may readily adapt it for diversified application without omitting certain features that constitute essential characteristics of the generic aspect thereof. Accordingly all such adaptations should—and are intended to—be comprehended within the meaning and range of equivalency fairly accorded the following claims.

15. Having thus described my invention, I claim:—

1. A valve for internal combustion engines having a hollow stem, a co-axial tubular conduit within said stem terminating short of the valve with provision of an annular clearance, means for circulating a lubricative-cooling medium therethrough and around the valve stem, and means for dissipating heat accumulated by said cooling medium during circulation.

2. A valve for internal combustion engines having a hollow stem, a co-axial stationary conduit within said stem defining an annular clearance, means for circulating a lubricative-cooling medium through the conduit and annular clearance as well as around the hollow stem, means for reciprocating the valve, and a radiator effective to dissipate heat from the circulating medium.

3. A valve for internal combustion engines having a hollow stem, a co-axial conduit within the stem defining an annular

clearance, means for circulating a lubricative-cooling medium therethrough and thereabout with circuitous flow, and means for effecting reciprocation of the conduit coincident with opening and closing of the valve.

4. A valve unit for internal combustion engines comprising relatively reciprocable co-axial induction and exhaust valves having hollow interiors defining a circuitous course for lubricative-cooling medium therethrough and thereabout, and means for radiating accumulating heat therefrom.

5. A valve unit for internal combustion engines comprising relatively reciprocable induction and exhaust valves having tubular stems, a co-axial conduit defining flow-and-return passages through said stems, means for circulating a lubricative-cooling medium therethrough and about the respective tubular stems, and a radiator for said valve effective to dissipate accumulating heat.

6. A valve unit for internal combustion engines comprising relatively reciprocable induction and exhaust valves having tubular stems, a co-axial conduit defining flow-and-return passages through said stems, means for circulating a lubricative-cooling medium therethrough and thereabout with forced feed, means for relatively opening and closing the aforesaid valves, and a radiator for said unit functional to dissipate heat accumulated during circulation of the cooling medium.

In testimony whereof, I have hereunto signed my name at Philadelphia, Pennsylvania, this 10th day of January, 1925.

JOHN W. SMITH.
